UNITED STATES PATENT OFFICE.

WILLIAM L. BEAR, OF WILLIAMSPORT, PENNSYLVANIA, ASSIGNOR TO THE PERFECTION CHECK PROTECTOR COMPANY, OF WILLIAMSPORT, PENNSYLVANIA, A CORPORATION OF DELAWARE.

PAPER-MARKING DEVICE.

1,030,963.

Specification of Letters Patent.

Patented July 2, 1912.

Application filed June 23, 1910. Serial No. 568,590.

To all whom it may concern:

Be it known that I, WILLIAM L. BEAR, a citizen of the United States, and a resident of Williamsport, county of Lycoming, and State of Pennsylvania, have invented certain new and useful Improvements in Paper-Marking Devices, of which the following is a specification.

My invention relates to devices for protecting checks, etc. by perforating portions of the checks on which the money values are written.

A particular object of the invention is to provide a simple, efficient and cheap device of this character which may conveniently be carried in the pocket.

A further object of the invention is to so construct and arrange the device that it may be used as an attachment on a fountain pen case or pencil.

A further object is to combine an inking device with the perforating device so that the appliance not only perforates but at the same time inks the perforations, thus rendering an erasure or alteration of the check doubly difficult.

The characteristics and advantages of the invention will be further described so far as is necessary in connection with a detailed description of the accompanying drawing which shows exemplifying structures in which the invention is embodied.

In the drawing: Figure 1 is a perspective view of one form of the invention adapted as an attachment for a pencil. Fig. 2 is a similar view of another form of the invention adapted as an attachment for a fountain pen. Fig. 3 shows the device of Fig. 1 in position for use. Fig. 4 is a section in the plane of rotation of the wheel showing the perforating and inking mechanism of either Fig. 1 or Fig. 2. Fig. 5 is a section similar to Fig. 4 of a modified form of the device. Fig. 6 is a perspective view showing a modified form of cap. Fig. 7 is a sectional view of a modification.

The mechanism of the perforating and inking devices proper will first be described with reference to Figs. 1, 2 and 4.

Reference character 1 designates a casing, conveniently of sheet metal and open at the top. A perforating roll or wheel 2 is journaled in the casing on a pin 3 and the serrated face of the roll protrudes from the casing as shown in Fig. 3. The projections

or teeth 11 on the face of the roll may be of any suitable form or arrangement for the purpose intended. Instead of being mounted on a pin, the roller may be provided with trunnions having bearings in the casing.

In the lower portion of the casing, in contact with the perforating wheel, and mounted revolvably on a pin 4, is the inking roll 5 which may be of any suitable material such as felt. A slot 6, conveniently located in one side of the casing adjacent to the inking roll, provides means for re-inking the same. When not in use, the roll is covered by a shield or cap 7 (Fig. 1), the side arms 8 of which are pivoted at 9 on a pin passing through the housing. One of the arms 8 is indented, as at 10, to form an inner projection engaging the face of the housing to hold the cap frictionally in closed position.

To use the device, the inking roll having been inked, the cap 7 is thrown back to the position shown in Fig. 3 and the roll 2 is applied to a portion of the check on which a money value is written and the device is moved along on the face of the check with suitable pressure so that the projections or teeth 11 of the marking wheel bite into the paper. At the same time, as the wheel revolves, it receives ink from the inking roll and this ink is applied to the perforations in the paper. The shield 7 when in active position, forms a convenient rest for the forefinger of the user by means of which the desired pressure may be easily applied to the device while it is moved across the face of the check.

To insure more complete protection of the perforating wheel when the device is not in use, a modified form of cap shown in Fig. 2 may be provided. In this form of the invention cap 7^a is cup-shaped and when in closed position fits down over and entirely closes the open end of the housing 1. The side arms 8^a of the cap are provided with slots 12 and the shaft 4 of the inking roll is extended to form studs 4^a engaging the slots. To use the appliance, the cap is swung to the position shown in dotted lines 105 by first raising it clear of the housing and swinging it around on the studs 4^a as a pivot. Another modified form of cap is shown in Fig. 6. In this construction the cap 7^b consists of a U-shaped piece of metal 110

hinged near one corner on studs 13 so that it swings on the housing in a plane transverse the axis of rotation of the perforating wheel. This cap is placed in open and closed positions in an obvious manner.

5 In Fig. 1 the appliance is shown adapted as an attachment for a pencil. For this purpose the housing 1 is provided with a tubular extension 15 which has on one side 10 a slit 16. The extension 15 forms a socket to receive the end of the pencil 17 which forms a convenient extended handle for the perforating appliance.

15 In Fig. 2 the device is shown adapted as an attachment for a fountain pen. The tubular extension 15^a has a longitudinal slit 18 and also a semi-circumferential slit 19 at the top of the longitudinal slit. This permits ample spring action of the lower part of the 20 socket to enable it to firmly and easily grasp the upper end of the cap 20 of a fountain pen. The socket 15^a is provided with a tongue 21 having a cupped end 22. This tongue forms a spring clip by which the pen 25 carrying the perforating appliance may be secured to the user's pocket. By cupping the end 22 of the clip a bowl-shaped inner surface is formed for engagement with the fabric of the pocket to insure firm attachment and at the same time prevent injury 30 to the fabric.

A modification of the perforating and inking device is shown in Fig. 5. In this form of the invention the housing 30 occupies 35 a yoke-shaped member 31 in the upper end of which the perforating roll is mounted. The inking roll is revolvably mounted on a sleeve 32, the ends of which are secured in the yoke. The yoke is held in place in 40 the housing by a pin 33 passing through tube 32 and engaging the sides of the housing. In this form of the device the pin is also extended to provide at 34 pivotal connection for the cap 7. By removing the pin 45 33 the yoke 31 may be removed from the housing and the inking roll is then readily accessible for repair or replacement or another yoke carrying a new inking roll and perforating wheel may be easily and cheaply 50 inserted and secured in position.

55 In Fig. 7 is shown a modified form of the marking and inking device in which an auxiliary inking device 40 is placed in the base of the housing adjacent to the inking roll 5. This auxiliary device may take the form of a stationary inking pad in contact with the roller. An aperture in the housing may be provided at 41 to apply ink to the pad. This pad constitutes a storage device 60 holding a suitable amount of ink by which the inking roller is continually replenished. The auxiliary inking device may also take the form of a second roller revolvably mounted in the housing in contact with inking roll 5. This auxiliary roller provides addi- 65

tional ink capacity and also serves to equalize the distribution of ink on roller 5.

I contemplate many variations in the construction of the invention in addition to those shown and described.

70

I claim:

1. In a paper marking device, the combination of a handle, a housing open at one end, a perforating wheel revolvably mounted near the open end of the housing, and a 75 protecting cap comprising side arms fixedly pivoted at the sides of the housing and a center portion connecting the side arms, the cap being constructed and arranged so that when in closed position the center portion 80 protects the wheel and when in open position the center portion rests against a portion of the housing to provide a rigid finger support.

2. In a paper marking device the combination of a handle, a housing thereon open at one end, an inking roll in the housing, a marking wheel revolvably mounted at the open end of the housing in contact with the inking roll, and a substantially U-shaped 90 cap having side arms fixedly pivoted to the sides of the housing, and a center portion connecting the arms and serving in one position to protect the wheel and in the other position to lie against the handle and form 95 a rigid finger support.

3. In a paper marking device, the combination of a handle, a housing thereon open at one end, an inking roll in the housing, a marking wheel revolvably mounted at the 100 open end of the housing in contact with the inking roll, and a substantially U-shaped cap having side arms pivoted to the housing and constructed and arranged in one position to protect the marking wheel and in 105 the other position to lie against the handle and form a firm finger support to apply pressure to the wheel.

4. In a paper marking device, the combination of an open-ended housing, a tube at 110 the closed end thereof to receive a pencil or the like, a yoke within the housing, a marking roll carried by the yoke, an inking roll within the yoke engaging the marking roll, and a bearing pin passing through the yoke 115 and housing forming a bearing for the inking roll and serving to retain the yoke in position in the housing.

5. In a paper marking device, the combination of an open-ended housing, a tube at 120 the closed end thereof to receive a pencil or the like, a yoke within the housing, a marking roll carried by the yoke, an inking roll within the yoke engaging the marking roll, a bearing pin passing through the yoke 125 and housing forming a bearing for the inking roll and serving to retain the yoke in position in the housing, a cap having side arms and serving to protect the marking roll in one position and in the other position to 130

engage said pencil tube and provide a rigid finger support.

6. In a paper marking device, the combination of a housing open at one end, a yoke 5 therein, a perforating wheel revolvably mounted in the end of the yoke, a tube secured in the yoke near the base thereof, an

inking roll mounted on the tube, and a pin passing through the tube and engaging the housing to hold the yoke in position.

WILLIAM L. BEAR.
